UNITED STATES PATENT OFFICE.

JAMES GEORGE EVANS, OF TUNBRIDGE WELLS, ENGLAND.

CHILD'S MAILCART AND LIKE VEHICLE.

Application filed February 21, 1921. Serial No. 446,855.

(GRANTED UNDER THE PROVISIONS OF THE ACT OF MARCH 3, 1921, 41 STAT. L., 1313.)

To all whom it may concern:

Be it known that I, JAMES GEORGE EVANS, a subject of the King of Great Britain and Ireland, residing at 54 High Street, Tunbridge Wells, England, have invented certain new and useful Improvements in Children's Mailcarts and like Vehicles (for which application for patent was made in Great Britain, #493, dated January 6, 1920, and 10 patent received on said application on June 6, 1921, patent being numbered 164,406), of which the following is a specification.

This invention relates to children's mailcarts and like vehicles and has for its object 15 to provide a strong, durable and effective construction, which permits of the mailcart being readily folded when out of use, or for the purpose of carriage from place to place and in which the seat is elastically supported, and thus effectively to absorb road shock or vibration.

According to the invention the seat is provided with its respective parts pivotally connected together in such a manner that it is 20 capable of being folded down when out of use or for transport, but the substantially vertical members or other parts of the seat frame or parts connected therewith are suspended from the frame by means of spiral 25 springs.

A handle is carried by means of rearwardly extending frame members which are pivotally connected to the respective parts 30 of the main frame, and these frame members are connected to the rear upstanding frame members of the back of the seat by means 35 of links, so that thus when the frame members carrying the handle are turned forwards, the frame members of the back of the seat are carried downwardly, and the 40 frame of the seat thus collapses and comes to lie immediately over the top of the main frame so that thus the height of the mailcart is considerably reduced, and a relatively 45 small space is taken by it.

In the position of use the frame members carrying the handle are held in their rear 50 position as for example by means of a pair of links, each link being divided and its respective parts pivotally connected together and the outer ends of the links connected respectively to one of the frame members carrying the handle and the adjacent frame

part of the frame, so that thus the links 55 may be caused to yield on the frame members of the handle being turned down.

According to the invention moreover the main frame consists of two parts disposed in parallel positions and made of metal tubes and secured at the respective ends of 60 the two axles of the road wheels. These main frame members may take a more or less oblong form in a vertical plane with the ends curved advantageously to a circular curvature so that thus the folding seat is 65 well supported.

According to the invention I provide a hood for such a mail cart comprising frame members carried by the back part of the seat or provided as upward extensions thereof. 70 These frame members serve to support the rear part of the hood while the forward part is supported by collapsible struts or stays. It will thus be understood that such a hood may be turned rearwardly when not in use and its front part may be turned rearwardly by the forward part of the strut or stay on each side moving upon the pivot pins so that it may come to lie in a depending 75 position at the rear of the seat, while that part of the struts or stays carried by the back of the seat then assumes a position 80 more near the vertical. Such a hood may have flexible extensions at the sides extending downwardly from the pivoted struts or stays referred to.

In the accompanying drawings,

The figure is a perspective view of the device.

In carrying the invention into effect according to one construction as illustrated in Figure 1, I provide the mail cart with four road wheels *a* of equal diameter, and I secure upon the respective axles *b*, two main frame members *c c* in position adjacent the 95 respective wheels. These frame members *c c* are provided of the oblong form substantially as hereinbefore described, from a tube. Each has a straight and substantially horizontal lower part and a straight and 100 slightly inclined upper part in the same plane, the inclination being slightly upwardly towards the front, so as thus to correspond with the normal inclination of the seat, while the ends of the respective main 105 frame parts *c c* have a circular curvature.

These respective parts *c c* may be conveniently provided of a single tube, or they may be formed of a number of tubes brazed or otherwise connected by a coupling member *b* so as to produce a very strong and durable construction.

Beneath the upper parts of these frame members lugs or brackets *d* are provided for the reception of the upper ends of spiral springs *e*, so that thus the seat *f* may be supported from two positions, that is at the front, and the rear at each side. It will be understood that the respective parts of the main frame are so spaced apart as to accommodate the seat between them, and that they may be suitably braced together by transverse members especially in large sizes of vehicles.

The seat *f* is provided so that the members of the back and front may be folded down in the manner hereinbefore described, but these respective members *g h* of the seat are extended downwardly to form extensions for the reception of the ends of the spiral springs *e* before referred to. These members *g h* are pivotally connected together by link members *i* and *j*, the members *i* serving as arm supports or side supports for the seat and are connected to the members *h* at the upper end of the latter, while the members *j* serve to carry the seat proper *f*. The seat *f* may be secured to the members *j* by means of nails or in any other way, and the seat may take any suitable form, plain or upholstered. It may be made of flexible material such as canvas, or of a substance such as wood or papier mâché. The member *j* may, however, be formed as a quadrilateral frame. The spiral springs *e* are advantageously secured at their lower ends to the laterally protruding ends of rods *k*, which thus serve to support the seat, and the parts *g* and *h* may turn upon the rods *k* when the seat is to be collapsed.

It will be understood that the arm supports or members *i* are in the usual way pivotally connected to the members *g* at the back of the seat and to the upper ends of the front members *h* by means of pivot pins to permit of the seat or chair collapsing in the manner described.

The frame members *l* carrying the handle *l* are advantageously also provided of metal tubes, and at their upper ends they may be diverted rearwardly and inwardly for the purpose of carrying the handle *l*, and the handle may be provided of wood or any other suitable material of a substantially cylindrical or other form, with recesses at the respective ends of the handle into which the respective inwardly protruding ends of the frame members may fit or be secured.

The frame members *l* carrying the handle are pivotally connected to the frame mem-

bers *c* on the inner side at *c²* and they are connected to the members *g g* of the seat by means of a pair of links *m* in the manner before described, and a pair of collapsible links *n* are provided for supporting the frame members *l* carrying the handle *l* from the respective main parts *c* of the frame at points *c¹* forward of the points *c²* at which the ends of the frame members *l* are pivotally secured in the manner before described.

The links *n* may be so constructed of parts pivotally connected together at *n¹*, that the link parts can only be moved upwardly from the position indicated in Figure 1, so that thus the links *n* may serve as struts in the use of the mail cart. Or instead the link parts may be connected together in any suitable manner as will permit of the link parts being moved in relation to each other; but again the links *n* may be provided as plain links and they may be disconnected at one of their ends when the mail-cart is to be collapsed.

A foot board *o* may be provided and may be supported by transversely disposed members which may be carried or secured to the brackets by means of which the main parts *c c* of the frame are secured to the wheel axles *b*.

It will be understood that the seat may take any suitable form. The seat may be provided without the upwardly extending members of the back *g g* and the seat may be constructed so that the supporting part thereof is disposed in a central position so that two children may for example be accommodated back to back looking one towards the front and the other towards the rear. In such a case it will be understood that a foot board such as *o* may be provided at each end. Again the members of the seat may be provided of metal and the parts *g g* and *h h* may for example be connected together by a transversely disposed part extending beneath the seat proper. Then again the seat may be constructed for the accommodation of the child in a reclining position. In such a case the construction is substantially the same as that hereinbefore described in that the seat would comprise members such as *g g* and *h h* spaced apart according to the accommodation required and connected together by link members such as *i* to permit of the seat collapsing in the manner hereinbefore described.

Moreover the members *g g* and *h h* in such a construction would be supported by means of spiral springs as hereinbefore described and the frame members *l* would be connected to the members *g g* or *i i* in order that these respective parts may be collapsed together. In such a construction moreover the parts *i i* may be formed into a quadrilateral or other shape closed figure and at the rear or

in front may be provided with a collapsible hood of a known kind. Such a construction might be adapted alternatively for the accommodation of the child in a sitting posture. Furthermore the mail-cart may be provided as an invalid chair.

Again the frame members carrying the handle may be dispensed with.

I claim:

10. 1. In a children's mail cart, in combination, two separate lateral and vertically disposed tubular metal frame members, said frame members each forming a closed figure, two transversely disposed axles respectively connected near the opposite ends to the lower parts of the said frame members, a seat, and means for carrying the seat from and between the upper parts of the said frame members, substantially as described.
20. 2. In a children's mail cart, in combination, two lateral and vertically disposed tubular metal frame members, the said frame members each forming a closed figure, two transversely disposed axles respectively connected near the opposite ends to the lower parts of the said frame members, a seat carried by and between the said frame members, and depending spiral springs by means of which the said seat is suspended from the upper parts of the said frame members, substantially as described.
30. 3. In a children's mail cart, in combination, two lateral and vertically disposed tubular metal frame members, the said frame members each forming a closed figure, two transversely disposed axles respectively connected near the opposite ends to the lower parts of the said frame members, a seat carried by and between the said frame members and comprising transversely disposed rods at the front and rear, and depending spiral springs by means of which the said

seat is suspended from the upper parts of the said frame members, substantially as described.

4. In a children's mail cart, in combination, two separate lateral and vertically disposed tubular metal frame members each forming a closed figure, two transversely disposed axles connected in opposite positions to the respective lower parts of the said frame members, a seat carried by and between the said frame members comprising two transversely disposed rods to which the lower ends of the respective vertically disposed frame members of the seat are connected, and spiral springs by which the said transversely disposed rods are suspended at their respective ends from the upper parts of the respective frame members, substantially as described.

5. In a children's mail cart, in combination, two separate and lateral and vertically disposed tubular metal frame members each forming a closed figure, two transversely disposed axles connected in opposite positions to the lower parts of the said frame members, a collapsible seat carried by and between the said frame members, the said seat comprising parallel disposed frame members at the front and rear whose lower ends are respectively carried upon two transversely disposed rods, means for suspending the said transversely disposed rods from the upper part of the said frame members, and a pivoted handle frame, the respective ends of which are pivotally connected to the frame members at the rear and links by which the said handle frame is connected to the rear frame members of the seat, and means by which the handle carrying frame is rigidly held in the position of use, substantially as described.

JAMES GEORGE EVANS.
